UNITED STATES PATENT OFFICE

WALTER B. PEDELTY, OF MASON CITY, IOWA

PULVERIZING PROCESS AND APPARATUS REISSUED

Application filed February 27, 1929. Serial No. 343,078.

This invention relates to improvements in pulverizing processes and apparatus of the general type employed for feeding finely divided fuel to furnaces.

5 In apparatus of this general type it is common to mount upon a single shaft a set of breakers or grinders and a centrifugal fan for delivering the finely divided portions of material into the furnace. In the use of such 10 apparatus for feeding blast furnaces great difficulties have been experienced by reason of the larger particles falling to the bottom of the retort while only partially consumed and becoming mixed with molten metal to 15 form a slag which is very difficult to remove, blasting operations being sometimes resorted to for that purpose.

To overcome this difficulty various expedients have been tried, one of the most common being to provide a wall or shoulder between the breaking or grinding portion of the apparatus and the fan in order to obstruct the passage of the larger fragments into the fan while allowing the smaller fragments to be thrown over such wall or shoulder. This expedient has proven effective to a considerable extent in keeping the larger fragments out of the fan but it has not prevented slag forming fragments from passing 20 through the fan to the furnace.

The primary object of my invention is to reduce pulverizable materials by entraining such materials in an elastic fluid and churning or impacting them against each other in a field or maelstrom of eddies induced by the operation of a centrifugal fan at one side of said field, the materials or fragments of materials being caused to impinge upon each other throughout the field while moving freely and promiscuously in various directions.

40 My invention is distinguished from a pulverizing apparatus in which materials and air are mechanically propelled and driven into contact with each other in such a manner as to produce crushing and abrading contacts, and which propelling operation requires to be many times repeated in order to reduce solid materials to the condition of a powder or a dust. In the practice of my 45 process, the material is preferably drawn

into the pulverizing field by suction and after it has once entered such field it is held in suspense without contact with moving mechanical driving mechanism until reduced to the desired degree of fineness determined by the 55 carrying capacity of an outflowing or centrifugally discharging stream of air.

More particularly stated it is an object of my invention to provide a fan which will effectively agitate small fragments of fuel and similar material or materials capable of being entrained in air and pulverized by impact of one portion upon another within a fan casing and at one side of the fan wings as to cause them to break or pulverize each other 60 so completely that the material may be delivered from the fan casing substantially in the form of dust and whereby solid fuels such as coal may be so pulverized as to be substantially capable of suspension in the heated 65 atmosphere of the furnace or retort until fully consumed.

70 My invention rests upon the discovery that a fan may be so constructed that the major portion of the material will not reach the 75 space occupied by the wings until after it has been caught in one or more powerful eddies or conflicting air currents and thrown violently against other particles of the material with impacting and grinding effects, whereby the material is almost instantaneously reduced to a size having the characteristic of 80 dust in that it is capable of being held in suspension in the atmosphere for a considerable 85 period of time.

It may therefore be stated that it is an object of this invention to provide a process for utilizing violently agitating air to effect a final pulverization of material and to deliver such material in an air stream 90 wherein it is capable of floating until consumed in a combustion chamber.

In the drawings:

Figure 1 is a side elevation of a pulverizing apparatus embodying my invention.

Figure 2 is a sectional view of the fan as taken on line 2-2 of Figure 1.

Figure 3 is a detail side view of the fan.

Like parts are identified by the same ref-

100

erence characters throughout the several views.

In the practice of my process I first reduce the material to small fragments by any suitable means, these fragments being preferably of such fineness that they can be entrained and carried in high velocity air streams. Thereupon I feed these fragments into a maelstrom of violently agitating air having a multitude of gyrating or cross currents of such intensity as to entrain the particles of material and throw them violently against each other and against any obstruction in their path. The velocity and force of the air currents is proportioned to the force required for crushing the particles of material when brought in contact with each other in the described manner.

My process also contemplates a continuous delivery of dust laden air from one side of the agitating field in which the fragments are being crushed and a corresponding continuous delivery of fragments to be reduced into said field from another side.

My preferred means for practicing the process and for feeding the material into and out of the space within which the material is being reduced, will now be described more particularly with reference to the accompanying drawings.

In the drawings, a breaker 10 of ordinary construction is conventionally illustrated, from which fuel or other material may be delivered through a chute or passage 11 to an inlet opening 12 of a centrifugal fan casing 13. The breaker and the passage 11 may be of any ordinary construction, or any desired means may be substituted for initially reducing the material into comparatively small fragments such as have heretofore been delivered to furnaces.

The casing 13 is similar in form to the casings of centrifugal fans in common use, the inlet 12 being located at the so called eye 45 or in the side wall of the casing opposite that at which the shaft 14 enters and the outlet passage or chute 15 being tangential in order that the fan wings may throw air and other material in the desired direction.

I have discovered that by mounting upon the shaft 14 a set of fan wings 17, preferably two wings diametrically opposite and of a width approximately one half to nearly two thirds that of the casing, it is possible to set up gyrating currents and cross currents in the portion of the casing between the wings and the inlet side, and thereby throw the fragments of material violently against each other and against the peripheral wall portion 55 18 of the casing in such a manner as to almost instantly reduce said fragments to dust.

If the fragments enter the spaces between the wings 17 to any considerable extent I am unable to find any evidence of that fact.

The wing surfaces do not become polished and the encircling peripheral portion of the casing does not become polished, even after prolonged periods of use. It is evident that if any fragments enter the space between the wings they are immediately thrown laterally and caught in the swirls and cross currents at the side of the wings. Air and finely divided particles are, however, constantly delivered through the outlet chute 15 in which no fragments of sufficient size to be classed as other than dust have as yet been discovered, although repeated tests have been made of the material passing through this chute.

The rapidity with which fragments of coal or similar material may be reduced to a dust indicates that the vortex or maelstrom developed in the open space between the inlet and the fan wings is composed largely of a multitude of eddies each revolving about its own axis, whereas, all of these eddies also travel in a circular path about the central axis of the fan shaft extended. Also, there appears to be a pulsating movement due to the fact that, as the fan revolves, the air in the space which it occupies tends to become compressed in front of the wings and a vacuum tends to develop in the rear of the wings with the result that the air in front of the wings is not only driven outwardly by centrifugal force, but develops a strong tendency to flow laterally into the space between the fan and that wall of the casing which is provided with the inlet, whereas, air and other material in such space tends to develop a counter-flow toward the rear side of each wing. The air and other material entering through the inlet, is also necessarily flowing in a general direction perpendicular to the plane of the vortex, and the combined effect is to increase the random element to a point where collisions take place with almost inconceivable frequency.

It also appears probable that the multitude of cross currents, developed by the pulsating effects of the fan wings and by the incoming material, operate to so diminish the general movement of revolution about the central axis as to prevent centrifugal force from developing in the vortex space to a degree sufficient to carry the larger fragments out of the vortex zone, and this appears to account for the fact that only dust laden air passes through the outlet chute.

In my improved fan I employ wings 17 having flat convergent surfaces, the wings being therefore wedge shaped, with the tips or outer margins substantially parallel to the shaft axis. Fan wings of this general type are disclosed in my former patent for a centrifugal fan dated September 27, 1927 and numbered 1,463,317 but for the purpose of my present invention I prefer to construct

these wings of cast steel, suitably cored to reduce their weight.

Apparently the form of the wings and the fact that but two diametrically opposite wings are employed, are material factors in developing the necessary agitation in the air between the inlet and the wings. However this may be, as compared with results obtainable from some of the other types of fans, it is certain that in a large part the results above described are obtained by reducing the width of the wings so as to allow a considerable space between them and the inlet side of the fan casing. I have found that with wings constructed as above described I obtain the best results by mounting the wings on the shaft in close proximity to the closed wall of the casing and provide space between them and the inlet side of the casing, of a width more than half that of the wings.

Such a fan delivers the fuel dust in a pulsating current of high frequency, and these pulsations are also an effective aid to combustion in that they tend to break up circulation streams of the gases in the combustion chamber.

By employing a two wing fan having a diameter of about twenty two inches from the tip of one wing to the tip of the other with blades about eight inches in width, a casing inlet about sixteen inches in diameter, and an outlet about twelve inches square, with approximately four and one-half inches between the inlet side of the casing and the fan wings, and by revolving such a fan at approximately 2000 R. P. M., I am enabled to completely reduce the coal fragments to a dust and to deliver such dust to a burner in a pulsating current as above described, without causing the fan wings to become abraded or even polished and with only a light polishing effect upon that portion of the casing which encircles the four and one-half inch space at one side of the fan wings.

I claim:

1. The process of pulverizing and feeding fuel consisting in generating a zone of multiple eddies and cross currents having a general path of revolution about a common axis, feeding fragments of solid fuel into said zone along said common axis whereby the fragments are driven against each other to crush the same by impacts and grinding contacts of such intensity as to reduce the fuel fragments to a dust, and delivering such dust, entrained in a portion of the eddying air, out of the space occupied by the eddies.

2. The process of pulverizing material consisting in generating a field of high velocity cross currents and eddies having a generally circular movement about a common axis and delivering fragments of pulverizable material into such currents, to be carried by the currents of air into contact with each other to pulverize the same by impact

and frictional contact preparatory to delivery by centrifugal force resulting from said revolution about the common axis.

3. The process of pulverizing and feeding fuel consisting in generating a vortex, feeding fragments of fuel into such vortex at one side thereof, and subjecting the vortex at the opposite side to pulsating agitation tending to develop cross currents and counter-currents.

4. The process of pulverizing material, consisting in generating a revolving, churning maelstrom of such material and an elastic fluid within an unobstructed whorl shaped space, feeding elastic fluid and material to be pulverized into said maelstrom at one side thereof, and delivering the pulverized material from said maelstrom tangentially when the particles are sufficiently reduced in size to be carried with portions of the elastic fluid out of said maelstrom by centrifugal force.

5. Apparatus for pulverizing fuel, comprising the combination with means for breaking the fuel into fragments, of a fan casing having its inlet disposed to receive such fragments, and a centrifugal fan rotor occupying substantially a half portion of the fan casing at the side opposite the inlet, said casing having a tangentially extending outlet passage.

6. Apparatus for pulverizing fuel, comprising the combination of means for breaking the fuel into fragments, of a fan casing having its inlet disposed to receive such fragments, and a centrifugal fan rotor occupying substantially a half portion of the fan casing at the side opposite the inlet, said casing having a tangentially extending outlet passage, and said fan rotor comprising a pair of oppositely extending flat surfaced wings.

7. The combination of a fan having a supporting shaft provided with a pair of oppositely extending wings, a casing for the wings of a width substantially double the width of the wings and arranged with said wings and provided with a side inlet, said wings being located within the casing adjacent to the side opposite the inlet, and means for feeding fuel through the inlet in fragments of a size to be lifted and thrown against each other by the air between the fan wings and the inlet.

8. The combination with a coal breaker of the furnace fueling type, of a centrifugal fan having a casing provided with an inlet to receive coal from the breaker, and also having a tangential outlet for delivering the fuel to the combustion chamber of a furnace, said fan having its casing containing a set of fan wings at the side opposite the inlet, and at a substantial distance from the inlet whereby the fragments of fuel and the air entering through the inlet may be agitated to reduce the fragments to a dust before de-

livery by the fan wings through the tangential outlet.

9. Pulverizing apparatus comprising a centrifugal fan casing provided with an inlet aperture in one side wall and a driving shaft extending through the other side wall and provided with a set of fan wings in close proximity to said last mentioned wall of materially less width than the width of the casing, the space between said wings and the wall provided with the inlet being open and unobstructed, and of sufficient capacity to allow air and the material to be pulverized to be drawn by suction through said inlet and churned in said space by currents induced by the revolving wings in such space.

10. Pulverizing apparatus comprising a centrifugal fan having a casing of materially greater width than the rotor, said rotor being located adjacent one side wall, and the opposing wall having an inlet duct for feeding air and material to be pulverized into the space at the side of the rotor by suction induced by the rotor, and means for revolving said rotor at a sufficient speed to develop a churning maelstrom in the space between it and the inlet, whereby the material may be reduced to a dust by impact and abrasion of the articles upon each other.
